(57) CLAIM

The ornamental design for an eye shadow brush, as shown and described.

DESCRIPTION

FIG. 1 is a front view of a eye shadow brush showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view thereof.

The broken lines shown in FIGS. 1-7 are included for the purpose of illustrating a portion of the eye shadow brush that forms no part of the claimed design.
